United States Patent Office.

CHARLES C. LLOYD, OF PHILADELPHIA, PENNSYLVANIA, ASSIGNOR TO THE AMERICAN METER COMPANY, OF NEW YORK, PHILADELPHIA, AND BOSTON.

Letters Patent No. 71,518, dated November 26, 1867.

IMPROVEMENT IN DRY GAS-METERS.

The Schedule referred to in these Letters Patent and making part of the same.

TO ALL WHOM IT MAY CONCERN:

Be it known that I, CHARLES C. LLOYD, of the city of Philadelphia, in the State of Pennsylvania, have invented a new and useful Improvement in the Dry Gas-Meter; and I do hereby declare that the following is a full, clear, and exact description of the construction and operation of the same, reference being had to the accompanying drawings, making a part of this specification, in which—

Figure 1 is a vertical section of the said improved meter on the left-hand side of the dotted line *w* of fig. 2.

Figure 2, a sectional front elevation.

Figure 3, a horizontal section below the dotted line *x* of fig. 1, and

Figure 4, an enlarged section of the hinge-joint which connects the flag and the bellows-disk together—

Like letters of reference indicating the same parts when in the different figures.

The object of my improvement is twofold, *i.e.*, to reduce the cost of construction, and to improve the action of the meter; and my invention consists in connecting the flag to the bellows-disk by the employment of a hinge-joint, constructed and applied substantially as hereinafter described; in producing the requisite horizontal arm of the flag-staff by bending the latter so as to dispense with an attachment of the arm as heretofore required for the purpose, and in maintaining a perfect parallelism between the bellows-disk and the partition of the meter during the movements of the former, by the application or employment of a coupling-arrangement, substantially as hereinafter described and set forth.

Referring to the drawings; A, B are usual dry-meter case; C, the flag-staff; D, the flag; E, the bellows-disk; F the hinge-joint, and G G' G'' the coupling-arrangement between the partition *a'* and the disk E. The wire which forms the flag-staff C, has its upper end extended and bent down to a horizontal position, so as to produce the requisite horizontal arm *c'*, as shown in fig. 1, thus avoiding the necessity of attaching a separate piece to the top of the staff to produce the arm, and affording not only a better, but a more reliable, strong, and easily constructed means of connecting the staff to the usual valve-rods, which latter, being constructed and arranged as heretofore, need not to be shown in the drawings. The flag D and the bellows-disk E, constructed as heretofore, are connected together by means of a vertical stem, *f'*, which is rigidly fixed to the flag D, and two brackets *f''* *f'''*, which are rigidly fixed so as to project on the outside of the disk, in the relation to each other shown in figs. 1, 2, 3. The head of the upper bracket *f''* has a socket bored nearly through it, from its under side, and fits loosely thereby over the rounded or conical upper end of the stem *f'*, so as to support the weight of the disk E upon the said end of the stem, whilst the lower end of the said stem passes loosely through the head of the lower bracket *f'''*, and thus keeps the disk E steady during its motions. The upper side of the head of *f''* has a small hole, 4, for the introduction of a lubricant. Heretofore the joint at this part has been formed by making a thicker stem, having a journal and shoulder at each end, the journals passing respectively through both of the brackets, and supporting the disk E upon the upper shoulder, thus not only requiring that the journals and shoulders be turned in a lathe so as to work smoothly in the bracket-holes, but causing also more friction; whereas in my improved joint, the stem being merely a straight piece of wire, requires only that its upper end be rounded or smoothed off, substantially as shown in fig. 4. It therefore greatly lessens the cost of constructing the joint, and affords an easier motion to the disk. The coupling-arrangement consists of a bracket, G', rigidly fixed to and projecting perpendicularly from the partition *a'*, and jointed to a bar, G, which is jointed to another bracket, G'', rigidly fixed to project inward on the inner side of the disk E, as shown in figs. 1 and 3. The length of the bar G, between its pivot-points, corresponds exactly with the distance between the centre of the flag-staff C and the centre of the stem *f'*, connected therewith by the flag D; and the distance between the pivot-point of the bracket G'' and the centre of the stem *f'*, corresponds precisely with the distance between the pivot-point of the bracket G' and the centre of the flag-staff C, and consequently the radial movements of the flag D, and of the bar G, are always simultaneous and parallel with each other, and therefore a perfect parallelism is maintained between the disk E and the partition *a'* at all times. Heretofore an imperfect sort of parallelism has been effected by means of a "bridle" of wire, applied to rock or turn on the bottom of the case A, B, and at the same, slide in slotted studs fixed on the outside of the disk E, but its operation is not only irregular and imperfect, but the "bridle" is very liable to get out of order; whereas my said improved mode of maintaining the

parallelism required, is perfect in its operation for the purpose, not liable to spring or get out of order, and is more easily constructed and applied.

Having thus fully described my improvement in the dry gas-meter, what I claim as new therein of my invention, and desire to secure by Letters Patent, is confined to the following, viz:

1. I claim making the flag-staff C, and its horizontal arm c' in one piece, by bending it as described and set forth, for the purpose specified.

2. I claim connecting the flag D to the bellows-disk E, by means of a hinge-joint, consisting of the vertical stem f' and the brackets f'' and f''', when the said parts (f' f'' f''') are constructed and connected together, in the manner described and shown, for the purposes specified.

3. I also claim maintaining the requisite parallelism between the bellows-disk E and the partition a', during the motions of the former, by means of the coupling-arrangement G G' G'' combined therewith, substantially as and for the purpose described.

CHAS. C. LLOYD.
